FIG. 4

FIG. 5 505^a

Burt A. Peterson

By Luther L. Miller, Atty.

UNITED STATES PATENT OFFICE.

BURT A. PETERSON, OF ROCKFORD, ILLINOIS, ASSIGNOR, BY MESNE ASSIGNMENTS, TO
EDGAR S. NETHERCUT, OF EVANSTON, ILLINOIS.

WINDER.

Application filed December 3, 1919. Serial No. 342,214.

To all whom it may concern:

Be it known that I, BURT A. PETERSON, a citizen of the United States, residing at Rockford, in the county of Winnebago and 5 State of Illinois, have invented certain new and useful Improvements in Winders, of which the following is a specification.

This invention relates to winders of the general type exemplified in Patent No. 10 1,267,977, dated May 28, 1918. The machine shown in said patent is adapted to rewind bobbins to form cross-wound yarn masses or "cheeses", and while the present invention is not necessarily limited to any particular type of yarn mass the invention will 15 be disclosed in connection with a machine for producing cheeses.

In the construction shown in the before-mentioned patent, means is provided for 20 detecting the fact that a cheese has reached the desired diameter. When such a cheese is reached by the traveling winder-tending mechanism or "traveler", devices are actuated to prevent any more thread from being wound on the cheese. These devices 25 include a pivotally mounted feeler or gage located in position to be carried into engagement with a full-size cheese. It has been found that a cheese will sometimes 30 lie in the path of the end of the gage and thus prevent the gage from functioning as well as causing breakage as the traveler endeavors to pass the cheese. Various causes 35 may result in a collision between the gage and a cheese; for example, the core on which the cheese is formed may become unlatched from its supporting arm and move laterally into such position as to foul on the adjacent arm and thus be held up in 40 the path of the gage; or a cheese may be so nearly full when passed by the gage that by the time the gage again reaches that unit the cheese will be oversize; or there may be misadjustment of the gage.

45 The object of the present invention is to provide means for stopping the travel and the operation of the winder-tending mechanism in case of an improper engagement of the gage with a cheese and to prevent the 50 winder-tending mechanism from being reset in operation until the cause of the stoppage has been removed.

In the accompanying drawings, Figure 1 55 is a fragmental front elevation of a winder embodying the features of my invention.

Fig. 2 is a fragmental elevation taken approximately in the plane of dotted line 2 of Fig. 1. Fig. 3 is a fragmental section view of the gage and a safety feeler co-operating therewith. Fig. 4 is a plan view 60 of the gage and the feeler. Fig. 5 is a fragmental view of the pivotal mounting for the gage. Fig. 6 is a view of a latch comprised in the mechanism.

In the drawings, *b* denotes tubular cores 65 on which yarn is wound to form cheeses *c*. Each core *b* is removably mounted upon a suitable support, as, for example, a hub 30^a such as the one shown in application Serial No. 74,290, filed January 26, 1916, by 70 Howard D. Colman (Patent No. 1,329,504, dated February 3, 1920). The hub is provided with means for locking the core in proper position on the hub. The hub is carried by an arm 30 which is pivoted at 31. 75 To economize space, the winding units are arranged relatively close together.

The winder-tending mechanism comprises a framework or carriage 89 arranged to travel along the winder and operate upon 80 the winding units in succession. The winder-tending mechanism comprises a roll 278 by means of which each cheese in succession is rotated in the direction to unwind yarn therefrom as a part of the end-finding operation. In the travel of the framework 89, a cam member 250 passes beneath the arms 30 and acts first to raise said arms and then lower them so as to place the cheeses upon the roll 278, after 90 which a roll 301 passes beneath the cheese.

Means is provided for gaging the cheeses while the latter are in contact with the roll 301. This means includes the gage or feeler 505 having a hub 505^a which is pivotally mounted upon a shaft 502^a. The shaft 502^a is mounted in suitable bearings in the framework 89. On said shaft is a stop arm 502^b (Fig. 2) which normally rests upon a stop plate 502^c whereby the normal position of the gage is determined. The gage 505 is adjustably connected to the shaft 502^a by suitable means, as, for example, that illustrated herein, said connecting means being substantially similar to that disclosed 105 in detail in Patent No. 1,267,977.

The end 506 of the gage 505 lies in the vertical plane occupied by the series of thrown-out cheeses, and is provided with a beveled surface 506^a (Fig. 3) which is adapt- 110

ed to engage a full cheese lying upon the roll 301 whereby the gage 505 is lifted and mechanism, not herein disclosed, is actuated to prevent any more yarn from being wound 5 upon the cheese. The line of arrows in Fig. 1 denotes the relative path of the upper portion of the periphery of a full cheese as the gage 505 approaches it.

In order to stop the mechanism in case a 10 cheese extends above the beveled surface 506^a, and hence in position to obstruct the travel of the gage, I provide a safety feeler lever 650 which is pivotally connected to the gage 505 at 651. One arm of the feeler 15 lever 650 terminates in a curved plate or broadened portion 652 that lies in advance of the forward end of the gage 506 so as to collide with any obstruction which extends above the path of movement of the beveled 20 surface 506^a. At the other end of the feeler lever 650 is a cup 653 in which lies loosely one end of a push-rod 654. The opposite end portion of the push-rod is slidably mounted in an opening 655 in the framework 89 and 25 lies in position to engage a lug 656 on a latch arm 657 which is pivoted to the framework 89 at 658.

The mechanisms on the framework 89 are driven and said framework is caused to 30 travel by power transmitted through a shaft 206. The shaft 206 is driven from a pulley 205 through a friction clutch member 209. The clutch member 209 is arranged to be controlled by means of a hand lever 214. 35 A contractile spring 216 connected to the hand lever 214 tends to throw out the clutch member 209. On the hand lever 214 is a projection 659 (Fig. 6) which normally lies against a locking shoulder 660 on the latch 40 arm 657. Below the shoulder 660 is a shoulder 661.

The operation is as follows: If a cheese resting upon the roll 301 is not of sufficient diameter to extend into the path of the 45 feeler portion 652 but does stand in the path of the beveled portion 506^a, the gage 505 will be swung upwardly, thereby actuating the mechanism that prevents additional yarn from being wound upon the cheese. If, however, 50 the cheese should be of such diameter as to be struck by the feeler portion 652, or if the cheese should be displaced so as to be supported by an adjacent arm 30 (see the cheese CX in Fig. 1), the feeler 650 will be 55 swung with reference to the gage 505, whereby the push-rod 654 will be forced against the lug 656, thus causing the latch arm 657 to swing upwardly. The lever 214 is thereby released to the action of the spring 216, 60 whereupon the clutch member 209 is thrown out and the carriage 89 stops. The pressure of the push-rod 654 against the lug 656 holds the latch arm 657 up; consequently, should the operator endeavor to restart the mechanism 65 without first removing the cause of the

stoppage, the projection 659 will stop against the shoulder 661 before the clutch member 209 is in effective position. When the cause of the stoppage is removed, the latch arm drops so as to permit the projection 659 to 70 be moved into position behind the locking shoulder 660.

I claim as my invention:—

1. A winder having, in combination, a member for gaging yarn masses, said member having a part which should not engage a yarn mass; and a feeler member located in position to engage a yarn mass which otherwise would engage said part. 75

2. A winder having, in combination, 80 a mean for gaging yarn masses, and means for automatically suspending the operation of the gaging means upon impending faulty coaction between the gaging means and the yarn mass. 85

3. A winder having, in combination, a support for a yarn mass, traveling means for gaging the yarn mass, and means for automatically suspending the travel of the gaging means upon impending faulty coaction 90 between the gaging means and the yarn mass. 90

4. A winder having, in combination, a support for a yarn mass, a pivoted gaging member arranged to travel into gaging relation with the yarn mass, and a feeler member arranged to travel and having a portion projecting in advance of the gage member. 95

5. A winder having, in combination, a support for a yarn mass, a gaging member 100 arranged to travel into gaging relation with the yarn mass, and means controlled by a feeler member mounted on the gage member for automatically suspending the travel of the gage member upon impending faulty coaction 105 between the gage member and the yarn mass.

6. A winder having, in combination, a support for a yarn mass, a gaging member arranged to travel into gaging relation with 110 the yarn mass, a feeler member, and means controlled by the feeler member for automatically suspending the travel of the gage member upon impending faulty coaction between the gage member and the yarn mass. 115

7. A winder having, in combination, a support for a yarn mass, a pivoted gaging member arranged to travel into gaging relation with the yarn mass, and means controlled by a feeler lever mounted on the 120 gage member for automatically suspending the travel of the gage member upon impending faulty coaction between the gage member and the yarn mass.

8. A winder having, in combination, a 125 support for a yarn mass, a carriage, means for driving the carriage, a hand lever controlling the driving means, a latch for locking the lever in driving position, a gage member pivoted on the carriage for gaging 130

the yarn mass, a feeler member mounted on the gage member, and means controlled by the feeler member for disengaging the latch from the hand lever.

5 9. A winder having, in combination, supports for yarn masses, a carriage, means on the carriage for gaging the yarn masses, and a feeler member for sensing an impending collision between the gaging means and a

10 yarn mass.

10. A winder having, in combination, a support for a yarn mass, a carriage, means for driving the carriage, a lever controlling the driving means, a latch for locking the

15 lever in driving position, means on the carriage for gaging the yarn mass, means for disengaging the latch from the hand lever upon impending faulty coaction between the gaging means and the yarn mass, and

20 means on the latch for preventing the return of the lever to driving position.

11. A winder having, in combination, a support for a yarn mass, a carriage, means for driving the carriage, a hand lever controlling the driving means, a latch for lock-

ing the lever in driving position, means on the carriage for gaging the yarn mass, and means for disengaging the latch from the hand lever upon impending faulty coaction between the gaging means and the yarn

30

12. A winder having, in combination, a support for a yarn mass, a carriage, means including a clutch for driving the carriage, means on the carriage for gaging the yarn

35

mass, and means for automatically throwing out the clutch upon impending faulty coaction between the gaging means and the yarn mass.

13. A winder having, in combination, a support for a yarn mass, a carriage, means including a clutch for driving the carriage, means on the carriage for gaging the yarn

40

mass, a feeler member associated with the gaging means, and means controlled by the

45

feeler member for throwing out the clutch.

In testimony whereof, I have hereunto set my hand.

BURT A. PETERSON.
